UNITED STATES PATENT OFFICE.

CLINTON C. CHILD, OF GRINNELL, IOWA.

DESIGN FOR A CORNER-PIECE.

SPECIFICATION forming part of Design No. 35,089, dated September 17, 1901.

Application filed May 28, 1901. Serial No. 62,291. Term of patent 3½ years.

To all whom it may concern:

Be it known that I, CLINTON C. CHILD, a citizen of the United States, residing at Grinnell, in the county of Poweshiek and State of Iowa, have invented certain new and useful Improvements in Corner-Pieces; and I do hereby declare the following to be a full, clear, and exact description of the invention, such as will enable others skilled in the art to which it appertains to make and use the same.

This invention appertains to a design for corner-pieces for picture-frames of novel form and unique configuration, the outline appealing to the esthetic as well as possessing utility.

The essential features of the design are similar members having a right-angular disposition, the outer walls of the members being flattened and having inner extensions at their edges and the inner walls being parallel with and terminating a distance from a plane touching the edges of the outer walls and having the edges adjacent the angle connected by a web or filling-piece of approximately triangular form, the portion connecting the inner and outer walls being of arch form and the ends of the members being curved.

For a clearer understanding of the design reference is to be had to the appended description and the drawings hereto attached, in which—

Figure 1 is a perspective view of a corner-piece embodying the design and as seen from the rear side. Fig. 2 is a front or plan view of the corner-piece.

Corresponding and like parts are referred to in the following description and indicated in both views of the drawings by the same reference characters.

The corner-piece is composed of members arranged relatively at a right angle to each

other, each comprising an outer wall 1 and an inner wall 2, the two walls being parallel and connected by a part 3 of arched form. The wall 1 is of greater depth than the wall 45 2 and is provided at its inner or rear edge with inner extensions 4, as shown. The inner walls 2 of the members are connected by a filling-piece 5 of approximately triangular shape and in a higher plane than a plane 50 touching the edges of the walls 1. The triangular filling-piece 5 is in a plane parallel with a plane touching the edges of the walls, and its diagonal edge is straight. The surface is embellished by embossed ornamentation, substantially as shown, the same consisting of oblong figures or lines having rounded ends and tapering throughout their length and radiating from a central point of the edge of the triangular-shaped filling-piece 5 toward the angle inclosed between the aforesaid right-angular members. Parallel lines extend across the end portions of the members about in line with the inner walls to form a square corner, and diverged 65 lines extend diagonally of the square toward the outer corner, and overlapped rounded figures are arranged between the said diverged lines. The curved walls 3 have lanceolate-shaped figures branching from the inner 70 sides of the square at the corner.

Having thus described the invention, what is claimed as new is—

The design for a corner-piece, substantially as herein shown and described. 75

In testimony whereof I affix my signature in presence of two witnesses.

CLINTON C. CHILD. [L. S.]
